DESIGN FOR A GIRDLE

Stanley D. Kops, New York, N. Y., assignor to
Kops Brothers, Inc., New York, N. Y., a corpora-
tion of New York

Application July 17, 1933, Serial No. 48,744

Term of patent 14 years

To all whom it may concern:

Be it known that I, STANLEY D. KOPS, a citizen of the United States, residing at New York, in the county and State of New York, have invented a new, original, and ornamental Design for a Girdle, of which the following is a specification, reference being had to the accompanying drawing, forming a part hereof:

Figure 1 is a perspective view of a garment embodying the new design, taken from the front, and

Figure 2 is a similar view of the garment taken from the rear.

The design is characterized by the central area formed of square, depressed areas at the front substantially uniformly spaced from the upper and lower edges of the garment, while the depressed areas at the back extend less than half of the area covered at the front.

I claim:

The ornamental design for a girdle as shown and described.

STANLEY D. KOPS.
